UNITED STATES PATENT OFFICE.

ARTHUR FAGET, OF SAN FRANCISCO, CALIFORNIA.

CAR-DOOR CLOSURE.

970,806.

Specification of Letters Patent. Patented Sept. 20, 1910.

Application filed January 17, 1910. Serial No. 538,509.

To all whom it may concern:

Be it known that I, ARTHUR FAGET, citizen of the United States, residing at San Francisco, in the county of San Francisco 5 and State of California, have invented a new and useful Car-Door Closure, of which the following is a specification in such full and clear terms as will enable those skilled in the art to construct and use the same.

10 This invention relates to an apparatus for the purpose of precooling the air in refrigerator cars, the object being to reduce the temperature of the air in the car, together with the contents thereof, to the desired 15 temperature, prior to the shipment of the materials. It will be understood by those familiar with the art that it requires some considerable time to reduce the temperature of fruit and other perishable articles, 20 to suitable temperature for transit, if the materials are simply placed in the car and ice supplied to the bunkers. The disadvantage of this is that from three to five 25 days elapse before the desired low temperature is attained, during which time more or less decay may take place.

The apparatus illustrated and described in this specification is intended for the purpose of handling the air used in precooling 30 the car and contents, and the particular object of the invention is to distribute the cold air in the car in such a manner as to prevent injury to the materials to be cooled.

In precooling the car and contents, air is 35 used as cold as the articles to be cooled will permit, that is, with an ordinary refrigeration plant, say from freezing to several degrees below zero, the object being to detain the car as short a time as possible, and 40 to cool the fruit to a temperature of about 40° Fahr. in as short a time as possible. Since this air is so cold, it would freeze any fruit or other perishable vegetables very 45 quickly if allowed to strike the same directly. It therefore becomes necessary to provide means for diffusing the cold air in such a manner as to completely cool the air in the car together with the contents thereof, while at the same time preventing the cold 50 air from the refrigeration plant from striking the fruit or vegetables.

In the drawings, in which the same numeral of reference is applied to the same portion throughout the several views, Figure 55 1 illustrates a central vertical sectional view through one of the car door plugs, and

a portion of a car the pipe 8 being shown in full lines; Fig. 2 represents a front elevation of a portion of a car and one of the plugs; Fig. 3 represents a horizontal sectional view of one of the plugs and a portion of the car on a larger scale than Fig. 1; Fig. 4 is a plan view of a portion of a car, and one of the hatchway plugs; and Fig. 5 is a vertical sectional view of the plug 65 shown in Fig. 4 on the line 5—5 thereon.

The numeral 1 is applied to the car body, and 2 represents the side wall of the car, the said wall of the car being provided with doors 3—3. The doors are opened and a 70 plug 4 is inserted in the door opening, said plug having pneumatic tubes 5 to make a tight joint with the door jamb, lintel and sill. Near the upper portion of the plug there is a box-like casing 6, supported by 75 means of braces 7, into which an air-pipe 8 leads. The side of this plug next the car contents is provided with two cross-bars 9 and 10, said bars supporting a curved plate 11, which extends to the bottom of the box 80 6, and against which the air from the pipe 8 impinges on entering the car. This curved plate causes the air to be deflected upwardly, and in order that it may be properly distributed in the car, four other curved 85 plates 12, 13, 14 and 15, are connected with the plate 11. These four plates are curved laterally, and are straight vertically. The plates 13 and 14 are connected at 16, and form a curved wedge, while the plates 12 90 and 15 are spaced away from the plates 13 and 14, and are substantially parallel therewith. The result of this construction is that the air passing through the pipe 8 in the direction of the arrow, strikes the plate 11, 95 is directed upwardly, and is spread out in the shape of a fan by means of the plates 12 to 15, the body of the air forming the fan extending in the neighborhood of the car roof, and away from the car contents. 100 Where convenient, other plugs will be connected with the hatchways of the car and the air will be passed in through pipes 8 and within the car through the hatchways thereof. But under certain circumstances, 105 it may become necessary to reverse the current of the air, and since it is not desirable to change the car equipment, since there are great numbers of standard refrigerator cars, having a given equipment, a plug such as is 110 shown in Figs. 4 and 5 may be used. In this case the plug is provided with means

for making a tight joint with the hatchway of the car, substantially like the means shown in Figs. 1 to 3. The numeral 18 represents the car roof, 19 the running board 5 near the center of the car, and 20 the rim of the hatchway. In this hatchway is inserted the plug 21, having the air pipe 22 secured thereto by means of a flange 23, rings 24 being provided for the convenient handling 10 of the hatchway plug. Since the course of the air through the pipe 22 is directly down, the tendency would be to strike the body of material in the car and undoubtedly injure the same if continued for the length of time 15 necessary to cool the entire car contents, and since the hatchways of a car are placed near one end of the side of the car, substantially as illustrated in Fig. 4, it becomes necessary in this case to direct the air horizontally and toward the opposite side and 20 close to the roof of the car in a fan, substantially like the fan produced by discharging air from the box 6. This is accomplished by securing a series of three curved plates 25, 25 26 and 27 to the hatchway plug at the bottom of the pipe 22. Then, as the air passes into the car through the pipe 22, it will be driven in the path indicated by the bottom of the curved plates, thus spreading and dif- 30 fusing the cold air in the car close to the roof, and preventing injury to the car contents.

Having thus described my invention, what I claim as new and desire to secure by Letters Patent of the United States, is as follows:

1. In a plug for car doors, a frame, means to make said frame air-tight in a door open-

ing, an air pipe connected with said frame, and deflecting means interposed in the path 40 of the air to direct the air toward the roof of a car, as described.

2. In a plug for car doors, a frame, means to make said frame air-tight in a door opening, an air pipe connected with said frame, 45 and deflectors arranged in the frame at the end of said pipe so as to direct the air in a fan-shaped body toward the roof of a car, substantially as described.

3. In a plug for car doors, a frame, means 50 to make said frame air-tight in a door opening, an air pipe connected with said frame, and deflecting means interposed in the path of the air to direct the air toward the roof of a car, and comprising a series of curved 55 plates adapted to spread the air into a fan-shaped body near the roof of a car, as set forth.

4. In a plug for car doors, a frame, means to make said frame air-tight in a door opening, and an air pipe connected with said frame and adapted to direct the air passing through the frame in a fan-shaped body 60 near the roof of a car, said means comprising a series of laterally curved plates inter- 65 posed in the path of the air from the pipe, substantially as set forth.

In testimony whereof I have hereunto set my hand this 8th day of January A. D. 1910, in the presence of the two subscribed 70 witnesses.

ARTHUR FAGET.
